 Hydro-Pneumatic Bath Appliance Company,
 Atlantic City, N. J., a corporation of New Jersey

Application September 30, 1931, Serial No. 566,105

34 Claims. (Cl. 128—66)

This invention relates to bath apparatus of the type employed in administering fluid massage treatments that have a stimulating and healthful effect.

5 In prior applications, as for example the application of John S. Martin, Serial No. 517,089, filed February 19, 1931, there is disclosed a fluid massage apparatus embodying injector means whereby fluid jets, preferably comprising a mixture of a suitable liquid such as water and a suitable gas such as air, can be applied to the body of a patient to produce a vigorous, vibratory massage. The apparatus referred to is positioned with respect to the body of the patient 10 so as to massage the desired part of the body and once positioned the region of application of the massage is fixed. This makes necessary frequent adjustment of the apparatus and movement of the patient, or else the use of a large injector unit, in order to extend the application 15 of the massage. Moreover, it is generally thought that the benefits of massage treatment are closely related with stimulation of circulation in the blood vessels near the surface of the body so that to produce the most beneficial results the massage should be applied in such a direction as to cause the blood to flow through 20 these vessels toward the heart. In most cases muscular exercise on the part of the patient is also very desirable, but often the patient is incapable of self-exercise and the enforcement of 25 muscular exercise manually or by mechanical means is extremely painful. Fluid massage produced by the apparatus above referred to tends 30 to stimulate circulation in the blood vessels, but as it is constantly applied to the same region of the body it does not have the desired effect of forcing the blood toward the heart. Moreover, 35 adjustments of the relative positions of the apparatus and the body are necessary to vary the region of application of the massage, and the apparatus does not include any provision for enforcing muscular exercise by the patient.

One of the objects of this invention is to provide 40 fluid massage apparatus whereby the massage may be movably applied to the body or in other words whereby the region of application of the massage is caused to progress from one part of the body to another.

45 Another object is to provide fluid massage apparatus whereby the massaging effect is definitely to work the blood through the veins in the direction of the heart.

A further object is to provide fluid massage 50 apparatus embodying movable injector means so

constructed and arranged that the massage is applied to the body in one direction of movement of the injector means but not in another direction of movement thereof.

A further object is to provide a means which 60 enforces muscular movement or exercise without physical contact of the hand or of apparatus with the body of a patient.

A still further object is to provide a fluid massage apparatus which is adapted to enforce 65 movement of a part of the body of a patient to which the massage is applied.

Briefly stated, the invention includes the provision of a movably mounted injector unit and means for moving the same, so that the region 70 of application of the massage is caused to move without disturbing the apparatus or the patient. In the preferred form hereinafter described, the injector unit is caused to move in a reciprocatory path, and means are further provided for 75 rendering the injector unit ineffective in one direction of movement thereof. In this way the region of application of the fluid massage is caused to progress along the body of the patient in a direction to force the blood toward the 80 heart, this action taking place in one direction of movement of the injector means, while during return movement of the injector means no massage is applied to the body. This intermittent action of the injector unit may also be employed to enforce muscular exercise. For example, a paralyzed arm is lifted by the force of 85 the jets during the effective period of movement of the unit and is allowed to fall again when the jets are ineffective. The result is a recurring 90 massage treatment acting only in one direction and an enforced muscular movement.

Several embodiments of the invention have been 95 illustrated in the accompanying drawings, but it is to be expressly understood that said drawings are for purposes of illustration only and are not to be construed as a definition of the limits of the invention, reference being had to the appended claims for this purpose.

In the drawings, 100
 Fig. 1 is a side view of an apparatus embodying the invention;

Fig. 2 is a plan view of Fig. 1, parts being removed for the sake of clearness;

Fig. 3 is a longitudinal section taken on the line 105 3—3 of Fig. 2;

Fig. 4 is a section taken on the line 4—4 of Fig. 2;

Fig. 5 is a section taken on the line 5—5 of Fig. 1; 110

Fig. 6 is a somewhat diagrammatic section taken on the line 6—6 of Fig. 5;

Fig. 7 is a perspective view of a valve operating mechanism;

5 Fig. 8 illustrates another apparatus embodying the invention;

Fig. 9 is a plan view in section of the apparatus shown in Fig. 8;

Fig. 11 is a side elevation of another apparatus embodying the invention;

Fig. 12 is a bottom plan view of Fig. 11;

15 Fig. 13 is a section taken on the line 13—13 of Fig. 12;

Fig. 14 is a section taken on the line 14—14 of Fig. 11; and

Fig. 15 is a sectional view of a valve and operating mechanism therefor.

20 Referring first to the apparatus shown in Figs. 1 to 7, inclusive, the injector unit is movably mounted in a frame of any suitable type. In the form shown, a plate 1 of metal or other suitable material is provided with a plurality of supporting legs 2 and with a plurality of elongated slots 3. Where the frame 1 is formed of metal, the legs 2 and the slots 3 may be formed by a stamping operation, the material stamped out to form the slots being struck down as shown at 4 in Fig. 5 30 so as to form rounded edges and the legs 2 terminating in suitable feet 5 which may be of rubber or other suitable material. It will be understood that the entire side portions of the plate 1 may be bent down to form supporting flanges extending 35 the entire length of the plate instead of the legs 2.

Movably mounted in the frame is an injector unit of any suitable type. In the form shown, the injector unit is of the type described in the prior application above referred to and is illustrated 40 in detail in Figs. 5 and 6. A manifold 6, to which air or other gas may be conducted as hereinafter described, is provided with a plurality of tubes 7 which preferably lie below the slots 3 in the plate 1 and are closed at their ends away from the 45 manifold 6 in any suitable manner, as by means of an end plate 8. A second manifold 9, to which water or other liquid may be conducted as herein-after described, is provided with a plurality of tubes 10 which extend through the manifold 6 and within the tubes 7 and are closed at 8, said tubes 7 and 10 being concentric so as to provide 50 passages therebetween.

Means are provided whereby the liquid flowing 55 from the manifold 9 through the tubes 10 and the gas flowing from the manifold 6 through the tubes 7 are mixed and ejected in the form of jets. Referring to Fig. 5, nozzles 11 are secured in suitable openings formed in the outer tubes 7, said nozzles preferably extending movably between the 60 struck-down portions 4 of the plate 1. Nozzles 12 are secured in suitable openings formed in the inner tubes 10, said nozzles 12 extending concentrically within the nozzles 11. The liquid from the tubes 10, which is preferably under pressure, 65 is expelled through the nozzles 12 and 11 and the liquid jets entrain the gas from the tubes 7 so that the jets from the injector unit comprise a mixture of liquid and gas and produce a vigorous vibratory massage on the body of the patient. 70 It will be understood that if desired the liquid and gas may be interchanged, the gas passing through the inner tubes 10 and entraining the liquid from the outer tubes 7.

75 As above stated, the injector unit is mounted for reciprocation in the frame and while any

suitable means may be provided for moving the injector unit, the preferred form comprises a fluid operated means driven by the same liquid (or gas) which supplies the injector manifolds. In the form shown in Figs. 1 to 7, the injector unit is driven by a fluid operated motor of a type which makes it unnecessary to provide moving connections such as flexible hose to supply the fluid to the injector manifolds. Referring particularly to Fig. 3, a tube 13 is secured to the manifold 6, said tube being provided with an extension 14 passing through the manifold 6 and communicating with the manifold 9. The tube 13 is concentric with and adapted to slide within a stationary outer tube 15 to which is secured a stationary valve casing 16 having an inlet connection 17 whereby a suitable liquid such as water is supplied to the apparatus, said liquid passing into the telescoping tubes 13 and 15 and thence through the extension 14 to the manifold 9. The outer tube 15 and valve casing 16 are secured to the plate 1 in any suitable manner, as by brackets 18 and 19.

Since the liquid is under pressure, it tends to force the inner tube 13 out of the tube 15 or in other words toward the left as shown in the drawings, said tube 13 carrying with it the injector unit comprising the manifolds 6 and 9 and the tubes 7 and 10. During this movement of the injector unit, liquid is supplied to the nozzles 11 and 12 and these nozzles travel along the elongated slots 3 in the table 1. At the same time air is supplied to the nozzles preferably by means of telescoping tubes 20 and 21, the inner tube 20 being secured to the manifold 6 and the outer tube 21 being secured to the stationary bracket 18 and having a suitable connection 22 with a source of gas or air. It will be seen that during movement of the injector unit in this direction the jets are in action and that if the arm of a patient, for example, is laid on the table 1 the region of application of the massage can be caused to progress up the arm and to stimulate circulation while at the same time forcing the blood toward the heart.

When the travel of the injector unit has been completed, means are provided for returning the same to its initial position as shown in the drawings and preferably the fluid jets are rendered ineffective at the same time. Referring particularly to Fig. 3, a tube or rod 23 is positioned within the telescoping tube 13, one end of said rod 23 being provided with an arm 24 which extends outwardly through the end of the tube 13 and can be fixed in any desired adjusted position by suitable means such as set screws 25. The other end of the tube 23 is provided with a head 26 against which bears one end of a coil spring 27. The other end of spring 27 bears against a spring seat 28 which is movable within the tube 13 and also with respect to the rod 23. An outer coil spring 29 is secured at one end to the spring seat 28 in any suitable manner as by soldering or welding and is connected at its other end to a plate 30 which is anchored in the stationary tube 15 by means of a pin 31. During the travel of the injector unit described above, the rod 23 is carried outwardly with the tube 13 so that the head 26 of said rod compresses the spring 27 against the spring seat 28 and thereby in turn tensions the outer spring 29. Springs 27 and 29 are thus effective together to resist the above described movement of the injector unit under the action of liquid pressure and when the pressure is shut off the springs return the 150

injector unit to the position shown in the drawings. The action of the springs is to retard the movement of the injector unit in the direction in which the fluid jets are in action, so that the progression of the region of application of the massage is gradual, and thereafter to return the injector unit to its initial position quickly as soon as the liquid pressure is shut off. It will be seen that a single spring may be employed if desired, but two springs acting serially are desirable because in this way excessive changes in the length of the springs and excessive forces are avoided.

Any suitable valve mechanism may be employed for shutting off the liquid pressure as soon as the injector unit reaches the end of its effective stroke. In the form shown, a rotatable sleeve valve 32 is mounted in the valve casing 16 and is provided with indexing ports 33 whereby communication is established in one position of the valve between the inlet connection 17 and the tube 15. The sleeve valve 32 is rotated by suitable means operated by movement of the injector unit between the open position above described and a closed position in which the liquid supply to the fluid motor and injector unit is substantially shut off. Referring particularly to Figs. 2, 4 and 7, an operating rod 34 extends slidably through an opening in a bracket 35 carried by a stationary part of the mechanism and through an opening in the end of plate 8 of the injector unit. Stop collars 36 and 37 are adjustably secured to the rod 34 so that said rod is actuated in one direction or the other by the end plate 8 of the injector unit.

The movement of rod 34 is employed to control a valve operating mechanism which preferably embodies a resiliently actuated means for rotating the sleeve valve 32 between its open and closed positions. Referring to Figs. 2 and 7, one end of the rod 34 is connected at 38 with an operating lever 39 pivoted at 40 on the valve casing 16. A second lever 41 is pivoted at 42 on the valve casing 16, the adjacent ends of the levers 39 and 41 being provided with meshing gear teeth 43. Levers 39 and 41 are also connected by a tension spring 44 which tends to throw the two levers between two limiting positions defining the open and closed positions of the valve 32. Referring to Figs. 4 and 7, lever 39 is provided with an arm 45 having an elongated slot 46 in which engages a pin 47 on the end of an arm 48 secured to the valve operating shaft 49. As the injector unit reaches the end of its outward movement, the plate 8 engages the stop 36 and moves the rod 34, gradually swinging the levers 39 and 41 about their pivots until the coil spring 44 crosses the line of centers 40, 42. During this swinging movement of the levers, the valve 32 is not actuated because of the lost motion provided by slot 46. As soon as the spring 44 crosses the line of centers, levers 39 and 41 are snapped to their other limiting position and the valve 32 is rotated instantaneously to closed position. The limiting positions of levers 39 and 41 may be defined in any suitable manner as by means of a stop 50 (Fig. 4) secured to a stationary part of the apparatus and adapted to be engaged by a pair of lugs 51 on the lower end of the valve operating arm 48.

As soon as the valve is closed, springs 27 and 29 return the injector unit to the position shown in the drawings whereupon the plate 8 actuates the stop 37 and moves the rod 34, the levers 39 and 41 and the spring 44 acting to return the

valve to open position. During this return movement of the injector unit, the jets are inactive because the fluid supply is shut off and the tubes 7 and manifold 6 tend to fill up with water entering through the jet tubes, particularly when the supply of air or gas is not under pressure. Preferably therefore, the valve 32 does not completely close but leaves a small opening to provide just sufficient passage of liquid under pressure to the jets to keep them in operation to prevent water from filling up the tubes 7 and manifold 6.

During a period of operation of the apparatus the successive rapid closings of the valve 32 will cause a varying pressure to be set up in the inlet connection 17 which may build up momentarily beyond a desirable maximum. Accordingly pressure unloading means are preferably embodied in the apparatus which may be of any suitable type. As shown in Fig. 6, the end of the valve casing 16 is threaded and receives a hollow nut member 52. A valve seat 53 is formed in the valve casing and is normally closed by a valve member 54 urged into engagement with said seat by a spring 55 and thereby closing the unloading passages 56. When the pressure builds up sufficiently to overcome the pressure of the spring 55, the valve 54 is moved and passages 56 are opened to relieve the fluid pressure. The tension of spring 55 may be regulated by adjusting the nut 52.

Preferably means are likewise provided for controlling the speed of travel of the injector unit in either direction. In the form shown, a stationary tube 57 is secured to the bracket 18 in any suitable manner as by means of a nut 58 (Fig. 4). A rod 59 extends slidably through one end of the tube and is connected at 60 with the movable manifold 6 of the injector unit. A piston member 61 is carried by rod 59 within a tube 57, and the escape of fluid from opposite sides of the piston takes place through discharge passages 62 controlled by needle valves 63. By regulating the setting of the needle valve, the speed of travel of the injector unit in either direction can be regulated as desired.

It will be seen that as the injector unit reciprocates, the jets are effective in one direction of movement to provide a massaging action and to stimulate circulation, forcing the blood in one direction, while during the return movement of an injector unit the jets are inactive. This intermittent action of the jets likewise enforces muscular action of the part of the body of the patient which is under treatment. For example, if the arm of a patient is laid on the table 1, the jets not only produce a powerful vibratory massage but also lift the arm bodily off the table. During the return movement of the injector unit the jets are inactive and the arm of the patient falls back by its own weight to the table. It will be understood that the apparatus is intended to be used under water, as in a bathtub or pool so that the result is to enforce an easy regular movement or exercise of the arm or other part of the patient being treated, the arm being moved back and forth without any actual contact of mechanical exercising means or of the hand therewith.

Figs. 8 to 10 illustrate the use of another apparatus embodying the invention which is larger than the portable unit illustrated in Figs. 1 to 7 and of somewhat different construction. In this apparatus, the plate or frame and the injector unit per se are substantially the same as those described above except that six slots are

80

145

150

provided in the table as shown in Fig. 10 and six sets of injector tubes are employed. Referring to Figs. 9 and 10, the apparatus comprises a table 64 provided with six elongated slots 65. The injector unit comprises a manifold 66 to which are connected six tubes 67 and a second manifold 68 to which are connected six tubes 69 extending within the tubes 67, the sets of tubes being provided with jets 70 as described above and being closed at their ends remote from the manifolds. In this unit, in order to provide greater operating power and to insure against binding of the telescoping parts constituting the fluid motor and fluid supply means, two stationary tubes 71 are provided at opposite sides of the apparatus, said tubes being secured to a stationary transverse header 72 that is secured to the plate 64 in any suitable manner. The injector unit carries two inner tubes 73 which slide within the tubes 71, said tubes 73 being provided with extensions 74 passing through the manifold 66 and communicating with the manifold 68. Air may be supplied to the manifold 66 by means of a tube 75 connected to and communicating with the manifold and an outer stationary tube 76 which is secured to the stationary header 72 and is provided with an inlet opening 77.

Each of the fluid motors embodies a single coil spring 78 which is connected at one end by means of a member 79 with the stationary tube 71 and at the other end with a rod 80 which extends through the manifolds 66 and 68 and is provided with a lock nut 81. A liquid such as water is supplied to the stationary header 72 through a suitable inlet opening and passes through the two fluid motors 71, 73 to the manifold 68 and thus through the tubes 69 and jets 70, while at the same time the gas passes through the manifold 66, tubes 67 and jets 70. The tendency of the liquid pressure is to force the injector unit outwardly against the tension of springs 78, during which movement the jets are active, and when the liquid pressure is shut off, the springs 78 return the injector unit to the position shown in the drawings. This movement of the injector unit may, if desired, be guided by rods 82 secured to the frame 64. It will be understood that the fluid motors may embody resilient means as described in connection with Fig. 3 if desired.

Preferably a single valve is employed to control the supply of liquid to the apparatus. As shown in Fig. 9, this valve is in the form of a sleeve 83 which is slidable in the transverse stationary header 72 and is provided with a port 84 registering in the position of Fig. 9 with the open end of one of the tubes 73, the valve terminating short of the open end of the other tube 73. A valve operating rod 85 is suitably connected at 86 with the valve sleeves and extends outwardly through the end of the header, terminating in a head 87. Suitably secured to the movable injector unit is an arm or bracket 88 carrying a rod 89 on which are formed two cam surfaces 90 and 91. As the injector unit moves outwardly or to the left as seen in Fig. 9, the rod 89 moves with it and the cam surface 91 engages the head 87 as the injector unit reaches the end of its stroke and pushes the head 87 and valve inwardly to the dotted line position shown in Fig. 9, thereby shutting off the liquid supply to the fluid motors except for a slight leakage to keep the jets open. When the injector unit has been returned to normal position, the cam surface 90 is effective to return the valve to the position shown in the drawings by virtue of its engagement with

the head 87. Preferably a spring 92 is provided to maintain the valve member in either of its limiting positions.

As shown in Fig. 8, the apparatus may be used in the bottom of a bathtub 93, the liquid inlet 82 being connected with the water spigot 94 in any suitable manner as by means of the hose 95 and the air inlet 77 being connected with the atmosphere through a suitable hose 96. In use, the tub should preferably be kept filled with water above the level of the cover plate 64. It will be understood that the apparatus shown in Figs. 1 to 7 inclusive is preferably used in the same manner.

Figs. 11 to 15, inclusive, illustrate another apparatus wherein a different type of operating motor is employed. The cover plate or frame 97 is preferably the same as the cover plate 1 and the injector unit comprises a liquid manifold 98 and tubes 99, a gas manifold 100 and tubes 101, and a plurality of jets 102, 103 as shown in Fig. 13, this unit being slidably mounted on supporting guide rods 104. Gas is supplied to the manifold 100 by a flexible hose 105, and liquid is supplied to the manifold 98 through a valve 106 carried on the end of said manifold and through a flexible hose 107. The structure of valve 106 is shown more clearly in Fig. 15, said valve comprising a sleeve 108 having a port 109 adapted to one position to register with the end of the manifold tube 98. A valve operating rod 110 is pivotally secured at 111 to the sleeve 108, said rod extending outwardly through the end of the valve casing and between suitable friction blocks 112 (Fig. 12).

As shown in Fig. 12, the injector unit has reached the end of its effective stroke during which the valve has been held in the position shown in Fig. 15 by the friction blocks 112 and rod 110. The position of the valve may be controlled by suitable means such as a stop collar 113 secured to the rod 110. As the injector unit begins its return stroke, the friction blocks 112 retard the rod 110 and the valve sleeve 108 is moved relative to the valve casing 106 until the port 109 no longer registers with the end of the manifold tube 98 except for a slight opening to permit sufficient leakage to keep the jets 102, 103 clear of water. Accordingly it will be seen that the jets are effective only in one direction of movement of the injector unit.

The injector unit is reciprocated by means of a fluid motor 114 of any suitable type, said motor having a fluid inlet connection 115 which may lead to the same source to which the hose 107 is connected and also with a fluid outlet 116. The reciprocating piston rod 117 of the motor 114 is connected by a rod 118 with a link 119 pivoted at 120, and the end of the link 119 is connected by a rod 121 with the injector unit at 122. The use of the rod 118, link 119 and rod 121 makes it possible where necessary to adjust the length of the stroke of the injector unit.

It will be understood that the invention is not limited to the particular form of injector unit illustrated and described. Any suitable injector means may be employed which produces the desired massaging action, but best results have been obtained with a jet comprising a mixture of liquid and gas. Moreover, the invention is not limited to the two forms of operating motors which have been illustrated and described, as any other suitable type of fluid motor may be substituted therefor and many of the advantages of the invention will be obtained with the use of a motor operated by other means than fluid pressure. The apparatus

- need not be portable, nor adapted for use in the usual bathtub, but may be embodied in permanent installations in hospitals and the like. Many advantages are likewise obtained by having 5 the injector unit movable but without provision for shutting off the jets in one direction of movement. Reference is therefore to be had to the appended claims for a definition of the limits of the invention.
10. What is claimed is:
1. In apparatus of the class described, the combination of injector means for discharging fluid jets adapted to provide a fluid massage, means for supplying fluid thereto, means for moving said injector means translationally with power supplied from a common source with said injector means whereby the region of application of the jets to the body of a patient is caused to move, and control means actuated by movement of said 15 injector means automatically controlling the action of said injector moving means and said injector means.
  2. In fluid massage apparatus of the class described, the combination of injector means for discharging fluid jets, means for supplying fluid thereto, fluid means for reciprocating said injector means whereby the region of application of the jets to the body of a patient is caused to progress in a desired direction, a source of fluid 20 common to said injector means and said injector moving means, and control means actuated by movement of said injector means automatically controlling the action of said injector moving means and said injector means.
  3. In fluid massage apparatus, the combination of injector means for discharging fluid jets, means for supplying fluid thereto, means for moving said injector means with source of power common with said injector means to cause the 25 region of application of the jets to move in one direction, and means common to said injector means and said injector moving means actuated by movement of said injector means for shutting off the fluid supply when the injector means moves in another direction.
  4. In fluid massage apparatus, the combination of injector means mounted for reciprocation and adapted to discharge fluid jets, fluid means for reciprocating said injector means with fluid supplied from a common source with said injector means, and valve means actuated by movement of said injector means for shutting off the fluid supply in one direction of movement of said injector means.
  5. In fluid massage apparatus, the combination of injector means for discharging fluid jets, fluid operated means supplied with a common source with said injector means for moving said injector means translationally whereby the region of application of the jets to the body of a patient is caused to move, and valve means for controlling the fluid supply to said fluid operated means, said valve means being actuated by movement of said injector means and automatically controlling the action of said fluid operated means, as well as the action of said injector means.
  6. In fluid massage apparatus, the combination of injector means adapted to discharge fluid jets, fluid operated means for moving said injector means translationally, means for supplying fluid to said injector means and to said fluid operated means from a common source of supply, and a common valve control means for said supplying means.
  7. In fluid massage apparatus, the combination of injector means, fluid operated means for moving said injector means, means for supplying fluid to said injector means and to said fluid operated means from a common source, means actuated by movement of said injector means for intermittently shutting off the fluid supply, and means for moving said injector means when the fluid supply is shut off.
  8. In fluid massage apparatus, the combination of injector means, fluid operated means for moving said injector means, means for supplying fluid to said injector means and to said fluid operated means from a common source, a spring opposing movement of said injector means in one direction, and means for shutting off the fluid supply whereby said spring moves said injector means in the opposite direction.
  9. In fluid massage apparatus, the combination of a frame having a cover plate provided with elongated openings, an injector unit movably mounted on said frame and having fluid jet means discharging through said openings, a fluid motor for moving said injector unit, and means for supplying fluid to said injector unit and to said motor.
  10. In fluid massage apparatus, the combination of a frame having a cover plate provided with elongated openings, an injector unit movably mounted on said frame and having fluid jet means discharging through said openings, a fluid motor for moving said injector unit, means for supplying fluid to said injector unit and to said motor, and valve means for shutting off the fluid supply to said injector unit.
  11. In fluid massage apparatus, a frame having a cover plate provided with openings, an injector unit movably mounted on the frame and having fluid jet means discharging through said openings, a fluid motor for moving said injector unit, an adjustable connection between said motor and injector unit to vary the length of travel of the latter, and means for supplying fluid to said injector unit and to said motor.
  12. In fluid massage apparatus, a frame having a cover plate provided with openings, an injector unit movably mounted on the frame and having fluid jet means discharging through said openings, a fluid motor for moving said injector unit, means for supplying fluid to said injector unit and to said motor, a valve carried by said injector unit for controlling the fluid supply to said injector unit, and a valve stem having frictional engagement with said frame, whereby said valve is open in one direction of movement of the injector unit only.
  13. In apparatus of the class described, the combination of a stationary member, a second member movable therein, said members constituting an expansible chamber, means for supplying fluid under pressure to said chamber to move said second member in one direction, resilient means opposing such movement, means for shutting off the fluid supply whereby said resilient means moves said second member in the opposite direction, an injector unit movable with said second member, and means for supplying fluid to said injector unit.
  14. Apparatus of the class described comprising a movable injector unit, means for supplying liquid and gas thereto, and fluid pressure operated means for moving said injector unit comprising a pair of telescoping tubes one of which is stationary and the other of which is movable and connected to said injector unit, a spring within and connecting said tubes, means connect-

- ing said tubes with a source of fluid pressure to move said movable tube in one direction, and means for preventing communication between said source and tubes whereby said spring moves 5 said movable tube in the other direction. 15. Apparatus of the class described comprising a movable injector unit, means for supplying fluid thereto, and fluid pressure operated means for moving said injector unit comprising a pair 10 of telescoping tubes one of which is stationary and the other of which is movable and connected to said unit, a spring within and connecting said tubes, a conduit connecting said tubes with a source of fluid pressure, and valve means operated by movement of said unit and tube for controlling 15 said conduit. 16. Apparatus of the class described comprising a stationary member, a second member slid- 20 able therein, said members constituting an ex- pansible chamber, means for supplying fluid under pressure thereto whereby said second member is moved in one direction, resilient means opposing such movement, valve means controlling the fluid supply and operated by movement of said second 25 member to shut off the fluid supply whereby said resilient means moves said second member in the opposite direction, an injector unit movable with said slid- 30 able member, and means for supplying fluid to said injector unit. 17. Apparatus of the class described comprising a stationary member, a second member slid- 35 able therein and constituting therewith an expansible chamber, means for connecting said chamber with a source of fluid under pressure whereby said second member is moved in one direction, resilient 40 means opposing such movement, an injector unit movable with said second member, means connecting said injector unit with a source of fluid, and means for shutting off the fluid supply to said injector unit and to said chamber whereby said resilient means moves said unit in the opposite 45 direction. 18. Apparatus of the class described comprising a pair of telescoping tubes constituting an ex- 45 pansible chamber, one of said tubes being sta- 50 tionary and the other movable, a spring within and connecting said tubes, means for supplying fluid under pressure to said chamber whereby the movable tube is moved in one direction against 55 the tension of said spring, an injector unit mov- 60 able with said tube, means for supplying fluid to said injector unit and to said chamber, and means for shutting off the fluid supply to said chamber and to said unit whereby said spring moves the movable tube in the opposite direction. 65 19. Apparatus of the class described comprising a stationary member, a second member slid- 65 able therein and constituting therewith an expansible chamber, means connecting said chamber with a source of fluid under pressure whereby said second member is moved in one direction, resil- 70 ient means opposing such movement, an injector unit movable with said second member, means connecting said injector unit to said source of fluid supply, and valve means controlling the fluid supply to said injector unit and to said chamber and operated by movement of said unit and member whereby said resilient means moves said second member in the opposite direction and the 75 fluid supply to said injector unit is simultaneously shut off. 20. Apparatus of the class described comprising a pair of telescoping tubes constituting an ex- 80 pansible chamber, one of said tubes being sta- 85 tionary and the other movable, a spring within and connecting said tubes, a conduit connecting said chamber with a source of fluid under pressure whereby said second member is moved in one direction, resil- 90 ient means opposing such movement, an injector unit movable with said second member, means connecting said injector unit with a source of fluid, and valve means controlling the supply of fluid to said chamber and to said injector unit, said valve means when in closed position providing sufficient leakage of fluid to said injector unit to keep the injector jets open. 21. Apparatus of the class described comprising a stationary member, a second member slid- 95 able therein and constituting therewith an expansible chamber, means for connecting said chamber with a source of fluid under pressure whereby said second member is moved in one direction, resil- 100 ient means opposing such movement, an injector unit movable with said second member, means connecting said injector unit with a source of fluid, and valve means controlling the supply of fluid to said chamber and to said injector unit, said valve means when in closed position providing sufficient leakage of fluid to said injector unit to keep the injector jets open. 22. Apparatus of the class described comprising a pair of telescoping tubes constituting an expansible chamber, one of said tubes being sta- 105 tionary and the other movable, a spring within and connecting said tubes, means connecting said chamber with a source of fluid under pressure, an injector unit movable with said movable tube, a fluid connection from said chamber to said injector unit, a valve operated on movement of said injector unit in one direction to shut off said fluid supply, a second pair of telescoping tubes one of which is stationary and the other movable with said injector unit, a connection from said injector unit to said second pair of tubes, and means connecting said second pair of tubes with another source of fluid. 23. Apparatus of the class described comprising a pair of telescoping tubes constituting an ex- 115 pansible chamber, one of said tubes being sta- 120 tionary and the other movable, a spring within and connecting said tubes, means connecting said chamber with a source of fluid under pressure, an injector unit movable with said movable tube, a fluid connection from said chamber to said injector unit, a valve operated on movement of said injector unit in one direction to shut off said fluid supply, a second pair of telescoping tubes one of which is stationary and the other movable with said injector unit, a connection from said injector unit to said second pair of tubes, and means connecting said second pair of tubes with another source of fluid, said valve when operated to closed position providing fluid leakage to said injector unit sufficient to keep the injector jets open. 24. Apparatus of the class described comprising a pair of spaced fluid motors each comprising a pair of telescoping tubes one of which is sta- 135 tionary and the other movable, springs within and connecting the tubes of each motor, a header connected with a source of fluid under pressure and having ports communicating with each of said motors, an injector unit, fluid connections from each of said motors to said injector unit, a valve controlling said parts and operated on movement of said unit to shut off the fluid supply to said motors, a third pair of telescoping tubes positioned between said motors, one of said third pair being movable and connected with said unit and the other being stationary, and means connecting said last named stationary tube with another source of fluid. 25. In fluid massage apparatus, the combination of injector means for discharging fluid jets, means for supplying fluid thereto, fluid means

for reciprocating said injector means, and fluid means independent of said reciprocating means for controlling the rate of movement of said injector means independently in each direction.

- 5 26. In apparatus of the class described, the combination of an injector unit having means for discharging fluid jets, means for supplying fluid thereto, means including a piston and cylinder for moving said injector unit, a stationary cylinder, a piston movable therein with said injector unit, and means for controlling the displacement of fluid by said piston to regulate the rate of movement of the same in said cylinder.

- 10 27. In fluid massage apparatus, the combination of a movable injector unit having means adapted to discharge fluid jets, a fluid motor for moving said unit, means for supplying fluid to said unit and to said motor, a valve controlling the supply of fluid to said motor, an operating member movable with said unit and adapted to move said valve between different positions, and operative connections between said operating member and said valve including a lost motion connection.

- 15 28. In fluid massage apparatus, the combination of a movable injector unit having means for discharging fluid jets, a fluid motor for moving said unit, means for supplying the fluid to said unit and to said motor, and means for controlling the fluid supply comprising a valve, a trigger mechanism for moving said valve between different positions, and an operating member movable with said unit for controlling said mechanism.

- 20 29. In apparatus of the class described, the combination of a movable injector unit adapted to discharge fluid jets, a fluid motor for moving said unit, means for supplying fluid to said unit and to said motor, and means for controlling the fluid supply comprising a valve, a lever for moving said valve, a spring for swinging said lever between different positions, and an operating member movable with said unit for controlling the action of said spring.

- 25 30. In apparatus of the class described, the combination of an injector unit adapted to discharge fluid jets, a fluid motor for moving said unit, means for supplying fluid to said unit and to said motor and means for controlling the fluid supply comprising a valve, a pair of pivotal levers having operative engagement at their adjacent

ends, a spring connecting said levers at points outside their pivots, an operating member movable with said unit and connected with one of said levers whereby said spring is effective to swing said levers to either of two limiting positions, and operative connections including a lost motion device between one of said levers and said valve.

31. In apparatus of the class described, the combination of a slotted bench, a movable injector unit adapted to discharge fluid jets through said slots, means for moving said unit, means for supplying fluid thereto, a valve actuated by movement of said injector unit for alternately shutting off the supply of fluid, and a relief valve in the supply line adjacent said controlling valve.

32. In apparatus of the class described, the combination of a slotted bench, a movable injector adapted to discharge fluid jets through said slots, means for supplying fluid thereto, valve means controlling the fluid supply, valve operating mechanism actuated by movement of said injector unit whereby the fluid supply is alternately shut off, and a relief valve associated with said valve means and adapted to open when the pressure exceeds a predetermined value.

33. In a fluid massage apparatus, the combination of injector means, means for supplying fluid thereto, fluid operated means for moving the injector means and means for supplying fluid thereto, a pair of springs opposing movement of said injector means in one direction, one of said springs being in tension and the other being under compression, and means for shutting off the fluid supply to said fluid operated means whereby said springs move the injector means in the opposite direction.

34. In fluid massage apparatus, the combination of a movable injector unit, means for supplying fluid thereto and a fluid motor for moving said unit comprising fluid operated means for moving said unit in one direction, a pair of serially connected springs opposing such movement, one of said springs being in tension and the other under compression, and means for shutting off the fluid supply to said motor whereby said springs move said injector means in the opposite direction.
